UNITED STATES PATENT OFFICE.

HENRY W. UNCKLES, OF NEW YORK, N. Y.; DAVID S. UNCKLES, ADMINISTRATOR OF
SAID HENRY W. UNCKLES, DECEASED.

INTERNAL-COMBUSTION ENGINE.

1,246,361.

Specification of Letters Patent. Patented Nov. 13, 1917.

Application filed June 27, 1914. Serial No. 847,577.

To all whom it may concern:

Be it known that I, HENRY W. UNCKLES, a citizen of the United States, and a resident of the city of New York, in the county and State of New York, have invented certain new and useful Improvements in Internal-Combustion Engines, of which the following is a specification.

My invention relates to internal combustion engines, and more particularly to apparatus for automatically starting such engines.

One of the objects of the invention is to provide a durable and efficient automatic starter for internal combustion engines.

Another object of the invention is to provide in such apparatus a fluid distributing device having a power-operated shiftable part for controlling the time of admission 20 of the air through the device to the cylinders, depending upon the desired direction of rotation.

Another object of the invention is to provide a durable and efficient air distributing device in which wear and tear on the valves is obviated by providing a "neutral" position at which the valves are inoperative.

Another object of the invention is to provide control apparatus whereby the starting 30 of the engine in either direction is entirely governed from a single master control device.

More specifically, my invention provides control apparatus comprising a master control lever having provision for controlling the shifting of the timer, the shifting of the shiftable member of the air distributor, the admission of air to said distributor, and the control of the circuit to the timer, in such 40 manner that the timer may be shifted for controlling the speed of the engine without affecting the distributor.

My invention also provides means whereby it may be utilized with a four-cycle engine. In such engines the shiftable cams operating the admission and the exhaust valves have to be shifted to one or the other of their positions, according to the desired direction of rotation of the engine; and for 50 this purpose I provide power-operated means for shifting said cams so that the entire control in starting a four-cycle engine in either direction may be had from the

master control lever without undue effort on the part of the operator.

My invention will be more readily understood and further objects of the invention will more fully appear from the following description taken in connection with the accompanying drawings in which—

55

Fig. 1 is a side elevation of a part of a three-cylinder two-cycle engine equipped with the preferred form of my invention;

60

Fig. 2 is a longitudinal sectional view of the distributing apparatus for distributing fluid to the cylinders;

65

Fig. 3 is a cross-sectional view of the same taken on line 3—3 of Fig. 2;

Fig. 4 is a cross-sectional view taken on line 4—4 of Fig. 2 and showing an operating cam;

70

Fig. 5 is a longitudinal sectional view showing the master control lever and its related parts;

Fig. 6 is a longitudinal section taken at 75 right angles to the view of Fig. 5;

Fig. 7 is a cross-sectional view taken on line 7—7 of Fig. 5;

Fig. 8 is a side elevation, partly in section, showing the invention as applied to a 80 four-cycle engine; and Fig. 9 is an end view of a portion of said apparatus.

I will first briefly describe the relative positions and connections of the different elements of the control apparatus, and I will 85 thereafter more fully describe the construction and operation of each.

Referring to the drawings (Fig. 1), 1 is the base of the two-cycle engine upon which are mounted the cylinders 2, 3 and 4. The 90 apparatus for distributing fluid to the cylinders for starting the engine is shown at 5, the shell of the apparatus being mounted on a bracket 6 secured to any suitable part of the engine such as the cylinder 2. The distributing apparatus, hereinafter more fully described, has pipes 7, 8 and 9 leading therefrom to the respective cylinders 2, 3 and 4, into which the fluid is admitted at proper periods during the engine cycle. 100 The distributing apparatus comprises a shiftable double cam 10 (Fig. 2) keyed on shaft 24 and shifted along the same by means of the fluid-pressure-operated piston 11 mounted in cylinder 12 and operating 105 upon rod 13 connected at its other end to

the cam, as hereinafter more fully explained. This cylinder 12 is formed integrally with the outer shell of the distributor 5 and connects through pipes 14 and 15 with ports 16 5 and 17 in the outer shell or sleeve 18 of a master control valve device 19 governing admission of air to piston 11. The cylinder also has a port 20 through which the air is admitted to the distributor.

- 10 A timer is provided having the usual inner and outer contact members. The outer member 21 is supported in a sleeve 22 loosely mounted upon shaft 24 so that the member 21 can be shifted about the shaft, and this 15 member is provided with contacts, one for each cylinder, connected by wires 27, 28, 29 to the respective spark plugs of the cylinders; while rotatable contact member 23 is keyed upon shaft 24 to rotate therewith. 20 This shaft carrying cam member 10 and contact member 23 is driven from the engine crank shaft by suitable gearing 25.

It is highly desirable to provide a single master control device for closing the circuit 25 to the timer, for shifting the shiftable member of the timer and that of the distributing apparatus and for admitting fluid to said apparatus, in order that the complete control of the engine for starting up in either 30 direction and for speed regulation, may be accomplished by this master control device. My invention provides for this complete control of the engine from a master control device, and in the present embodiment of 35 the invention I provide a master control lever 30 mounted on an insulating bushing 31 surrounding stub shaft 31 which is journaled in forks 76 from plate 32 journaled in the sleeve 18 at the outer end of bracket 40 84. This plate 32 contains valve mechanism for admitting air to either pipe 14 or 15 leading to cylinder 12, depending upon the position to which the lever 30 is swung.

The supporting plate 32 is connected with 45 the shiftable shell 21 of the timer by means of a link 35 in a manner hereinafter more fully explained, so that as the operator swings the lever 30 in a horizontal plane to rotate plate 32 in its "forward" or "reverse" 50 position to admit air to cylinder 12, the timer will at the same time be shifted in proper position for starting the engine in the proper direction. This lever 30 also controls, in a manner hereinafter more fully 55 explained, the circuit to the spark coil from battery 36.

Having thus generally outlined the relative positions of the timer, the air distributor and the operating and controlling mechanism by which they are controlled from the master control lever, I will now proceed to describe the construction and operation of these different parts.

Referring to Figs. 2 and 3, it will be seen 60 that the air distributing apparatus in the

present form of the invention, comprises an annular valve housing or shell 40 having a lower cylindrical extension 41 forming, with a detachable cylindrical head 42 at the opposite end of the shell 40, a chamber 43 70 inclosing the shiftable cam member 10.

The vertical shaft 24 geared to the crank shaft of the engine and carrying the cam member 10 and the timer member 23, extends through the chamber 43. The lever 13 75 for shifting cam member 10 is pivoted on the valve housing at 45. Each end of the lever is slotted so as to receive at one end a pin 46 projecting from the cam member and at the other end to receive a pin 47 projecting from the lower end of piston rod 48, so that as the piston 11 is moved up or down by the admission of fluid through pipes 14 or 15, the lever 13 is swung on its pivot 45 to shift the cam member 10 so as to bring one 80 or the other of the cam surfaces 49 or 50 in alinement with valve spindles 51 extending from valves 52 radially through the inner wall of the valve housing. The two cam surfaces 49 and 50 are arranged at pre-determined angles one to the other about the shaft 24 so that when one of them, say 50, engages the valve spindles it opens the valves 52 at predetermined periods relative to the cycle of the engine to admit compressed air 95 for forward rotation of the engine, while the other cam 49 when brought in alinement with the spindles 51, operates the valves to admit compressed air at predetermined periods such as will cause the reverse rotation 100 of the engine. The cam member 10 is cut away between the two cam surfaces 49 and 50 to provide an intermediate portion of insufficient diameter to engage the valve spindles, so that when the valve member is 105 shifted to its "neutral" position, i. e., the position at which the cut-away portion is in the plane of the spindles, the valves are not operated by the rotation of the shaft 24, which is continuous. In order to hold the 110 valve member in its "neutral" position when the fluid pressure is cut off from the cylinder 12, I provide a spring 53 secured to the hub of lever 13 and having its outer ends engaging pin 54, by which arrangement the cam member will be brought back to its "neutral" position whenever the fluid pressure from cylinder 12 is cut off. Compressed air to intake chamber 59 of the distributor is admitted from cylinder 12 through port 20 115 whenever the port is uncovered by double piston 11 and brought into communication with cylinder 12 above or below the piston. Surrounded by the intake chamber 59 there are a series of separate chambers 61, formed 120 by radial partitions 62 between inner and intermediate walls 63 and 64 of the valve shell. Communication between the intake chamber 59 and the series of separate chambers 61 is had through ports 60 controlled 125

130

by the valves 52. These chambers communicate respectively with the cylinders through openings 65, 66, 67, and pipes 7, 8 and 9. The valves 52 are normally held seated by 5 springs 52' the inner ends of which rest upon the valves and the outer ends upon clamped plugs 52'' which are threaded into the shell 40 in alignment with the valves so that the distance of the said plugs from the valves 10 may be adjusted to vary the compression of the springs 52'.

Referring now to Figs. 5, 6 and 7, it will be seen that the plate 32 on which the master control lever 30 is mounted, is provided with 15 a tapered lower projection 68 having a cored-out central chamber 69 with a radial passage 70 communicating therewith, which is brought into communication with the ports 16 or 17 by shifting the supporting 20 plate 32 within the supporting sleeve 18 to its "forward" or "reverse" position. The tapered valve core or projection 68 (Fig. 7) is also provided with cutaway portions forming passages 70', 70'' adapted, respectively, 25 to connect the pipes 14 and 15 with exhaust ports 14' and 15', depending upon whether the master control valve handle 30 is moved to the left or right to bring the passage 70 in alignment with pipe 15 or 14 to admit compressed air to one or the other of said last 30 pipes. The central cored-out chamber is provided with a disk valve 71 having a stem 72 extending upwardly through the center of the supporting plate 32 in position to be 35 engaged by the lower edge of the shank of the master control lever 30. The point at which the valve stem projects through the plate 32 is provided with packing inclosed in a suitable cap 73. The valve is held normally closed upon its seat by means of a coiled spring 74 pressing at its upper end against the valve and at its lower end supported within the mouth of connection piece 75 threaded into the bottom of extension 68. 40

45 The main supply pipe 38 from the source of compressed air, such as the compressed air tank 37, is secured to the connection piece by a swivel coupling 75', permitting the plate 32 to be swung around.

50 When the valve spindle 72 is depressed by a downward movement of the master control lever 30, compressed air is admitted through chamber 69 to passage 70, and from thence to one of the supply pipes 14 or 15 55 leading to the cylinder 12, depending upon the position in which the plate 32 has been swung in its horizontal plane of movement; so that by swinging the master control lever in its horizontal plane of movement to the 60 "starting" or "reverse" position, and pressing down on lever 30, the piston 11 will be moved to shift one of the cam surfaces 49 or 50 into the plane of the valve stem 51 so that the valves will be opened at the 65 proper times relative to the cycle of the en-

gine to start the engine in the desired direction of rotation. As soon as the piston 11 uncovers port 20 and puts the same in communication with the upper or lower end of the cylinder 12, compressed air is admitted 70 to the intake chamber 59, from whence it flows through the ports 60 to the cylinders as the valves 52 are opened by the rotation of the cam.

As the cam-actuating double piston 11 is 75 moved in one direction, as for example downward by the admission of compressed air through pipe 14, the air on the lower side of said piston is exhausted through pipe 15, passage 70'' and through exhaust 80 port 15'. In the same manner, if the compressed air was admitted by the control valve to pipe 15 to move the actuating piston 11 upwardly, the movement of the control valve in the direction to admit compressed air through passage 70 into pipe 15 for this purpose would simultaneously couple pipe 14 with exhaust port 14' through passage 70' to allow the air at the upper end of the cylinder to be exhausted.

The master control lever is mounted, as heretofore described, on bushing 31' of stub shaft 31 journaled between projecting forks 76 extending upwardly from the face of plate 32, and the lever is insulated from 95 said forks in any well-known manner (said means of insulation being well known and therefore not shown herein). The lever therefore, besides movement in its horizontal plane, may be moved in a vertical plane 100 to depress valve stem 72. Also on this plate 32, in alignment with the forks 76, there is a pair of projecting guides 77 in one of which I mount a contact plunger 78 positioned to 105 be engaged by the metallic shank of the control lever to close the circuit to the timer. In the present embodiment of my invention this contact plunger 78 is mounted in an insulating bushing 79 and is held normally thrust to its inner position by means of a 110 spring 80 mounted on an insulating block 81 upon the supporting plate 32, this spring 80 carrying at its upper end a binding screw to which a suitable lead 82 is secured. The outer end of the spring is always held 115 pressed in engagement with the head of the contact plunger 78 so that contact between the two is never broken, the circuit being made and broken between the shank of the master control lever and the contact plunger. This circuit is from battery 36, wire 82, through contact plunger 78, the shank of the master control lever, and through wire 83 to the spark coil 83' (Fig. 1) which 120 has its secondary connected to the timer through wire 83'', where connection is made to the rotating inner contact member in any well known manner. By this arrangement, the circuit to the timer is normally held 125 closed by the master control lever, and is 130

only broken when the master control lever is lifted above its normal position shown in the drawings. It will be seen that the shank of the lever is of such thickness that the lever is kept in engagement with the contact plunger while the lever is pressed down to open valve 71.

In order to shift the shiftable member of the timer by the master control lever at the same time that the valve plate 32 is shifted to admit compressed air to the cylinder 12, I connect the shiftable valve plate 32 and the shiftable member of the timer by means of the link 35 pivoted at each end on projections from these two parts. In this way, as the master control lever is shifted in its horizontal plane of movement, the timer is also shifted. If it is desired to move the timer through a greater arc of movement than the valve plate 32, this may be readily provided for by adjusting the respective lengths of the projections from these two parts to which the connecting link 35 is pivoted.

Having thus described the construction and operation of the different features of my invention, the method of operating and controlling the machine from the master control lever will readily be understood as follows:

To start the engine forward, the operator presses down upon the master control lever to close the circuit to the timer at the contact plunger 78. The lever now being in the starting position, passage 70 will be in register with pipe 14 for conveying air to the upper end of cylinder 12. Likewise, the timer will be in the proper position for forward rotation, and as the operator presses the master control lever farther down, valve stem 72 is pressed upon to open valve 71 and admit compressed air through pipe 14 to cylinder 12 to move piston 11 down and shift cam member 10 to its "forward" position, the compressed air at the same time passing from the upper part of cylinder 12 through port 20 to the intake chamber 59 as soon as the upper head of piston 11 uncovers the port 20; whereupon the compressed air passes from chamber 59 through whichever one of the valves 52 may be open, and to the corresponding cylinder to start the engine and shaft 24 rotating; and as shaft 24 rotates, the valves 52 are opened sequently at the proper periods to admit compressed air to the cylinders to continue the rotation of the engine. If the operator now desires to retard his spark, that is, to shift the timer, as is necessary in controlling the speed of the engine after it is started, he lifts the lever, or allows the lever to lift under the compression of spring 74 until valve 71 is closed, whereupon he may swing the lever to any suitable position in its horizontal plane of movement for regulating the posi-

tion of the timer according to the speed of the engine desired. The range of movement of the master control lever in its horizontal plane for shifting the timer will frequently be through a greater angle than the angle 70 between the ports 16 and 17 in the valve sleeve 18; so that during this shifting movement of the master control lever the radial passage 70 would register with the ports 16 or 17, causing, unless otherwise prevented, 75 the admission of compressed air to the cylinder 12, which would be undesirable even if the air were admitted in a manner to assist the engine in the proper direction of rotation, since it would interfere with the proportion of the fuel mixture; and if the admission of the air through the distributor should be such as to tend to reverse the engine, it would either shut down the engine or perhaps cause more serious trouble. But 80 this difficulty is avoided by the fact that the control valve 71 beneath the master control lever, is normally closed to shut off the supply of compressed air to the distributor except when the valve stem is deliberately depressed by the operator. If the operator desires to reverse his engine, he lifts his lever up, breaking the circuit to the timer, and then swings the lever to the "reverse" position, thereby swinging the timer to "reverse" 85 position and bringing passage 70 in communication with port 17 communicating with the lower end of cylinder 12, whereupon he presses down upon his control lever, admitting air through valve 71 to port 17 100 through pipe 15 to the lower end of cylinder 12, forcing the piston 11 up to throw cam 49 in alinement with the valve spindles 51 for opening the valves at the proper times for reverse rotation; and as the lower end 105 of piston 11 opens the port 20, compressed air flows from the lower end of cylinder 12 through port 20 into valve chamber 59, from whence it passes through the different ports 60 to the cylinders. 110

In Fig. 8 I have shown the invention as applied to a four-cycle four-cylinder engine, with provision for shifting the double cams controlling the intake and exhaust valves of the cylinders. It will be understood that in 115 the case of T-head cylinders used on four-cycle engines, it is usual to provide one cam shaft for operating the fuel intake valves and another cam shaft for operating the exhaust valves; while in the case of L or other 120 types of head than the T-head cylinders, the admission and exhaust valves are operated from the same cam shaft, or else automatic intake valves are used, so that in either event only one cam shaft is necessary. The 125 cam-shifting apparatus which I provide is capable of shifting one or both cam shafts as may be used, and I have illustrated the invention in connection with a four-cycle engine with T-head cylinders having two 130

cam shafts, one for the cams controlling the intake valves and another for the cams controlling the exhaust valves.

The air distributer 5' is mounted on a suitable bracket 6' that may be secured to any desired portion of the engine, while the timer may be mounted on shaft 24', in this instance a "half time" shaft upon which the distributer is also mounted in the manner previously described in connection with the two-cycle engine. The master control lever 30' is also arranged on the valve control device 19' mounted on a suitable bracket 34', all as hereinbefore described in connection with the two-cycle engine; and these different parts are operatively connected to each other and to the cylinders in the manner hereinbefore described, so that I will only describe the construction and control of the apparatus for shifting the cams.

Referring to Figs. 8 and 9, 85 is a cam shaft upon which is keyed a sleeve 86 bearing a series of double reversing cams 87 of the usual construction, the sleeve being shiftable along the shaft by means of a collar 88 operated by a bell crank lever 89 pivoted on a stub shaft 90. These cams 87 have two cam surfaces one for "forward" and one for "reverse" direction of rotation, as is well understood in the art, with an intermediate "neutral" portion, and they operate the exhaust valves through the intermediation of rollers 92 and suitable connecting mechanism, all as well understood in the art. This cam shaft is suitably geared to the crank shaft, as is well understood, and therefore not shown. Behind the shaft 85 there is a second shaft 95 (Fig. 9) upon which are mounted double cams 96 for operating the intake valves of the cylinders which are arranged on the shaft 95 in the same general manner as the cams 87 are arranged on shaft 85. Since the construction and arrangement of these are well understood in the art, I will not show nor describe them in any further detail.

The bell crank lever 89 has an elongated hub 97 upon the other end of which is mounted a second forked arm 98 engaging a collar 99 secured to the sleeve of shaft 95, so that the two cam sleeves are operated simultaneously by shifting the bell crank lever. In order to shift the cams in proper position at the same time that the shiftable member of the distributing apparatus is shifted and without undue effort on the part of the operator, I provide power-operated means for this purpose, and in the present embodiment of the invention this consists of a cylinder 100 containing a piston 101 pivoted at its lower end to one arm of bell crank lever 89. The cylinder communicates at its upper and lower ends respectively with pipes 102 and 103 which branch at connections 104 and 105 from pipes 14' and

15' leading from the master control valve device 19' to cylinder 12' of the air distributing apparatus, so that when the master control lever 30' is operated for shifting the cam member of the air distributing apparatus and admitting air through the distributer to the cylinders for "forward" or "reverse" rotation, the piston 101 is also operated to shift bell crank lever 89 for moving the cams 87 and 96 into their "forward" or "reverse" positions.

It will be seen from the above description of my invention that I have provided simple, durable and efficient apparatus for automatically starting the engine in either direction of rotation; and so arranged as to control the starting of the same as well as the speed of the engine from a single master control lever, so that the engine can be very readily and quickly controlled without any exertion on the part of the operator.

Those skilled in the art, in the light of my invention, will understand that various changes and modifications may be made in the different parts of the invention without departing from the spirit or scope of my invention, and while I have shown and described with particularity what I believe to be the best embodiment of the invention, it will be understood that in so far as certain features of my invention are concerned, different forms of air distributing apparatus and different forms of apparatus for actuating the distributer and the intake and exhaust valve cams, may be substituted for those shown, as well as other means of controlling the operation of the timer, the distributer and the cam shafts from the master control lever; and I aim in the appended claims to cover all such modifications and changes within the scope of my invention.

Having thus described my invention, what I claim as new and desire to secure by Letters Patent, is—

1. In an internal combustion engine, the combination with a plurality of cylinders having fuel intake control apparatus, of apparatus for distributing fluid to the cylinders to start the engine, said distributing apparatus including a part having ports communicating with the cylinders independently of said control apparatus and a part driven from the engine and controlling the distribution of the fluid through said ports, one of said parts being shiftable relatively to the other to change the time of distribution of fluid to the different cylinders relative to the engine cycle, for controlling the direction in which the engine starts, power-actuated means for shifting one of said parts to control the direction of rotation of the engine in starting, and a master control device controlling the power-actuating means to start or reverse the engine.

2. In an internal combustion engine, the

combination with a plurality of cylinders, of apparatus for distributing fluid to the cylinders to start the engine, said apparatus including a part having ports communicating with the cylinders and a part driven from the engine and controlling the distribution of the fluid to said ports, one of said parts being shiftable relatively to the other to change the time of distribution of air to the different cylinders relative to the engine cycle, for controlling the direction of rotation of the engine in starting, said shiftable part having a "forward," a "reverse" and a "neutral" position, means for shifting said part to its "forward" or "reverse" position for controlling the direction of rotation of the engine in starting, and means operatively related to said shiftable part for automatically returning said part to its "neutral" position.

3. In an internal combustion engine, the combination with a plurality of cylinders, of apparatus for distributing fluid to the cylinders to start the engine, said apparatus including a part having ports communicating with the cylinders and a part driven from the engine and controlling the distribution of the fluid to said ports, one of said parts being shiftable relatively to the other to change the time of distribution of air to the different cylinders relative to the engine cycle, for controlling the direction of rotation of the engine in starting, said shiftable part having a "forward," a "reverse" and a "neutral" position, power-actuated means for shifting said part to its "forward" or "reverse" position for controlling the direction of rotation of the engine in starting, means operatively related to said shiftable part for automatically returning said part to its "neutral" position, and a master control device controlling application of power to the power-actuating means.

4. In an internal combustion engine, the combination with a plurality of cylinders having fuel intake control apparatus, of apparatus for distributing fluid to the cylinders to start the engine independently of said control apparatus, fluid-pressure-actuated means controlling the flow of fluid through said distributing apparatus for starting and reversing the engine, and a master control device for controlling the flow of fluid to said fluid-pressure-actuating device, whereby the starting of the engine in either direction may be controlled by said master control device.

5. In an internal combustion engine, the combination with a plurality of cylinders, of apparatus for distributing fluid to the cylinders to start the engine, said apparatus including a part having ports communicating with the cylinders and a part driven from the engine and controlling the distribution of the fluid to said ports, one of

said parts being shiftable relatively to the other to change the time of distribution of air to the different cylinders relative to the engine cycle, for controlling the direction of rotation of the engine in starting, said shiftable part having a "forward," a "reverse" and a "neutral" position, fluid-pressure-operated means for shifting said part to its "forward" or "reverse" position for controlling the direction of rotation of the engine in starting, a pipe for supplying fluid to said last means, a valve controlling the flow of fluid through said pipe, and a master control device operatively related to said valve, whereby the starting and reversing of the engine may be controlled by said master control device.

6. In an internal combustion engine, the combination with a plurality of cylinders, of apparatus for distributing fluid to the cylinders to start the engine, said apparatus including a part having ports communicating with the cylinders and a part driven from the engine and controlling the distribution of the fluid to said ports, one of said parts being shiftable relatively to the other to change the time of distribution of air to the different cylinders relative to the engine cycle, for controlling the direction in which the engine starts, an electric timer comprising two relatively rotatable and relatively shiftable contact members one of which is driven from the engine, and a control lever operatively related to the shiftable member of the distributing apparatus and to the shiftable member of the timer for controlling the shifting of each, said lever having provision whereby the timer may be shifted without operating the shiftable member of the distributing apparatus.

7. In an internal combustion engine, the combination with a plurality of cylinders, of apparatus for distributing fluid to the cylinders to start the engine, said apparatus including a part having ports communicating with the cylinders and a part driven from the engine and controlling the distribution of the fluid to said ports, one of said parts being shiftable relatively to the other to change the time of distribution of air to the different cylinders relative to the engine cycle, for controlling the direction in which the engine starts, power-actuated means for shifting one of said parts to control the direction of rotation of the engine in starting, a device for controlling the application of power to said actuating means, an electric timer comprising two relatively rotatable and relatively shiftable contact members one of which is driven from the engine, and a master control lever operatively related to the shiftable member of the timer and having provision for also operating the control device of the power-actuated means of the distributor for controlling the

shiftable members of the timer and distributor to shift both or only the timer, whereby the control lever may shift the timer to control the speed of the engine without operating the fluid-pressure distributor.

8. In an internal combustion engine, the combination with a plurality of cylinders, of apparatus for distributing fluid to the cylinders to start the engine, said apparatus including a part having ports communicating with the cylinders and a part driven from the engine and controlling the distribution of the fluid to said ports, one of said parts being shiftable relatively to the other to change the time of distribution of air to the different cylinders relative to the engine cycle, for controlling the direction in which the engine starts, fluid-pressure-actuated means for shifting one of said parts to control the direction of rotation of the engine in starting, a pipe conveying fluid to said actuating means of the distributor, a valve controlling the flow of fluid through said pipe, an electric timer comprising two relatively shiftable contact members one of which is driven from the engine, and a master control lever mechanically connected to the shiftable member of the timer and operatively related to said control valve for causing both the shifting of the timer and the shiftable member of the distributor, or for shifting only the timer, whereby the control lever may shift the timer to control the speed of the engine without operating the fluid-pressure distributor.

9. In an internal combustion engine, the combination with a plurality of cylinders, of apparatus for distributing fluid to the cylinders to start the engine, said apparatus including a shiftable and rotatable cam member driven from the engine and having two cam surfaces with an intermediate portion, a valve casing surrounding the cam member and having a plurality of separate chambers communicating respectively with the cylinders of the engine, each chamber having an intake port thereto, means for supplying air to said ports; spring-seated valves closing the ports and having projections extending radially through the valve casing into position to be engaged by one or the other of the cam surfaces when the cam member is shifted, fluid-pressure-operated means for shifting the cam member to bring one or another of the cam surfaces into engagement with the valve projections depending upon the desired direction of rotation of the engine, a master control lever controlling the application of power to said cam-shifting means for controlling the direction of rotation of the engine, and means for returning the cam surface to its "neutral" position where the valve projections are not engaged by the cam surfaces.

10. In an internal combustion engine, the combination with a plurality of cylinders, of apparatus for distributing fluid to the cylinders to start the engine, said apparatus including a shiftable and rotatable cam member driven from the engine and having two cam surfaces with an intermediate portion, a valve casing surrounding the cam member and having a plurality of separate chambers communicating respectively with the cylinders of the engine, each chamber having an intake port thereto, means for supplying air to said ports, valves closing the ports to govern the flow of fluid to the cylinders, adjustable plugs secured in the valve casing in alignment with the valves, compression springs between the valves and the plugs for holding the valves closed, projections from said valves extending through the inner wall of the casing into position to be engaged by one or another of the cam surfaces when shifted into operative position, means for shifting said cam to its operative positions, and means for returning the cam to its "neutral" position where the valve projections are engaged.

11. In a four-cycle internal combustion engine, the combination with a plurality of cylinders having exhaust and intake ports with shiftable cams for controlling said ports, of apparatus for distributing fluid to the cylinders independently of said intake ports to start the engine, power-operated means for controlling the flow of fluid through said distributing apparatus and for shifting the cams for starting the engine in either direction of rotation, and a master control device controlling the application of power to said power-actuated means, whereby the admission of fluid to the cylinders and the shifting of the cams, for either direction of rotation, may be controlled by said master control device.

12. In a four-cycle internal combustion engine, the combination with a plurality of cylinders having exhaust ports with shiftable cams for controlling the operation of the same at different periods relative to the cycle of the engine, depending upon the direction of rotation, of fluid-pressure-operated means for shifting said cams for forward or reverse direction of rotation, apparatus for distributing fluid to the cylinders to start the engine, said apparatus including a part having ports communicating with the cylinders and a part driven from the engine and controlling the distribution of fluid to said ports, one of said parts being shiftable relatively to the other to change the time of distribution of the air to the different cylinders relative to the engine cycle, for forward or reverse direction of rotation, fluid-pressure-actuated means for shifting one of said parts to control the direction of rotation of the engine in starting, and a

master control device operatively related to both of said fluid-pressure-actuated means for controlling the operation of the same.

13. In a four-cycle internal combustion engine, the combination with a plurality of cylinders having exhaust ports with shiftable cams for controlling the operation of the same at different periods relative to the cycle of the engine, depending upon the direction of rotation, of power-actuated means for shifting said cams for forward or reverse direction of rotation, apparatus for distributing fluid to the cylinders to start the engine, said apparatus including a shiftable part controlling the time of distribution of the air to the different cylinders relative to the engine cycle, for controlling the direction in which the engine starts, power-actuated means for shifting said part to control the direction of rotation of the engine, a control device governing the application of power to both of said power-actuated means, an electric timer comprising two relatively shiftable contact members one of which is driven from the engine, and a master control lever mechanically connected to the shiftable member of the timer and operatively related to said control device for causing the shifting of the timer and the shifting of the shiftable part of the distributor and of the cams, or of the timer only, whereby the control lever may operate the timer to control the speed of the engine without reversing the engine.
14. In an internal combustion engine, the combination with a plurality of cylinders, of an electric timer comprising two relatively rotatable and relatively shiftable contact members one of which is driven from the engine, a circuit for the timer, a contact controlling said circuit, apparatus for distributing fluid to the cylinders to start the engine, said apparatus comprising a shiftable member for controlling the time of distribution of the fluid to the cylinders relative to the engine cycle, and a master control device operatively related to said contact and to the shiftable member of the timer and the shiftable member of the distributing apparatus, for controlling the circuit to the timer, the application of power to the distributor and the shifting of the shiftable members of the timer and the distributor, whereby the starting of the engine in either direction may be entirely controlled from the master control device.
15. In an internal combustion engine, the combination with a plurality of cylinders, of an electric timer comprising two relatively rotatable and relatively shiftable contact members one of which is driven from the engine, a circuit for the timer, a contact controlling said circuit, apparatus for distributing fluid to the cylinders to start the engine, said apparatus comprising a shift-
- able member for controlling the time of distribution of the fluid to the cylinders relative to the engine cycle, a master control lever operatively related to said contact and to the shiftable part of the distributor for controlling each, and means mechanically connecting the master control lever with the shiftable member of the timer, whereby the starting of the engine in either direction and the control of the speed of the same may be governed by said lever.
16. In an internal combustion engine, the combination with a plurality of cylinders, of an electric timer comprising two relatively rotatable and relatively shiftable contact members one of which is driven from the engine, a circuit for the timer, a contact controlling said circuit, apparatus for distributing fluid to the cylinders to start the engine, said apparatus comprising a shiftable member for controlling the time of distribution of the fluid to the cylinders relative to the engine cycle, a master control lever pivoted so as to have movement in two planes and operatively related to said contact and to said shiftable member of the distributing apparatus to control the same by movement in one of said planes and mechanically connected to the shiftable member of the timer to control the same by movement in the other plane, whereby the timer may be moved to control the speed of the engine without affecting the contact or the distributing apparatus.
17. In an internal combustion engine, the combination with a plurality of cylinders, of an electric timer comprising two relatively shiftable contact members one of which is driven from the engine, means including an external source of power for imparting movement to the engine, a member movable to control the application of power to the engine by said last-named means, and a master control lever mechanically connected to the shiftable member of the timer and operatively related to said power-control member for causing both the shifting of the timer and the moving of the control member, or for causing only the shifting of the timer whereby the master control lever may shift the timer to control the speed of the engine without operating the power-control member.
18. In a 4-cycle internal combustion engine, the combination with a plurality of cylinders having exhaust ports of shiftable cams for controlling the flow of gas through said ports at different periods relative to the cycle of the engine, depending upon the direction of rotation, apparatus for distributing fluid to the cylinders to start the engine, said apparatus including a shiftable part controlling the time of distribution of the fluid to the different cylinders relative to the engine cycle, for controlling the direction

in which the engine starts, power-actuated means for shifting said cams for forward and reverse direction of rotation and for shifting said part to control the direction of 5 rotation of the engine, a control device governing the application of power to both of said power-actuated means, an electric timer comprising two relatively shiftable contact members one of which is driven from the 10 engine, and a master control lever mechanically connected to the shiftable member of the timer and operatively related to said control device for causing the shifting of the timer and the shifting of the shiftable 15 part of the distributor and of the cams, or of the timer only, whereby the control lever may operate the timer to control the speed of the engine without reversing the engine.

19. In an internal combustion engine, the 20 combination with a plurality of cylinders, of an electric timer, comprising two relatively rotatable and relatively shiftable contact members one of which is driven from

the engine, a circuit for the timer, a contact controlling said circuit, apparatus including 25 an external source of power for initiating the rotation of the engine, a member movable to control the application of power to said engine, a master control lever pivoted for movement in two planes and operatively 30 related to said contact and to said movable member to control the same by movement in one of said planes, and mechanically connected to the shiftable member of the timer to control the same by movement in the 35 other plane whereby the timer may be moved to control the speed of the engine without affecting the contact or the control member.

In testimony whereof, I have signed my name to this specification, in the presence of 40 two subscribing witnesses.

HENRY W. UNCKLES.
